UNITED STATES PATENT OFFICE.

ABRAHAM NOVICK, OF NEW YORK, N. Y., ASSIGNOR TO F. L. SCHMIDT COMPANY, OF NEW YORK, N. Y., A CORPORATION OF NEW YORK.

WEB-CUTTING MECHANISM.

1,140,392.

Specification of Letters Patent. Patented May 25, 1915.

Application filed November 25, 1913. Serial No. 802,874.

To all whom it may concern:

Be it known that I, ABRAHAM NOVICK, a citizen of the United States, and a resident of New York, borough of Brooklyn, in the county of Kings and State of New York, have invented certain new and useful Improvements in Web-Cutting Mechanisms, of which the following is a specification.

This invention relates to web cutting mechanism and has for its object to provide means of the class specified, simple in construction, efficient in operation, and adapted for operating upon a moving web.

With these objects in view my improvements comprise features illustrated in their preferred embodiment in the drawings accompanying this specification, wherein—

Figure 1 is a front elevation of my improved cutting mechanism; Fig. 2 is a sectional side elevation on line 2—2 of Fig. 1, looking in the direction of the arrow thereof, and showing means for feeding a web toward and away from said cutting mechanism; Fig. 3 is a fragmentary sectional elevation on line 3—3 of Fig. 1; Figs. 4 and 5 are fragmentary sectional elevations respectively, on line 4—5 of Fig. 1, and illustrating successive steps in the operation of my improved mechanism.

Before describing the invention in detail I desire to have it understood that the invention is not limited to the particular construction and arrangement of parts which I have illustrated and shall hereinafter describe, and that various changes may be made in the mechanism shown without departing from the spirit or scope of the invention, and that the phraseology which I employ is for the purpose of description and not of limitation.

My improved web cutting mechanism comprises a pair of opposite, coacting cutters, each of which is mounted on an axis eccentric to a fixed axis, and means are provided for revolving those eccentric axes about their fixed axes respectively, and for rotating the cutters on their eccentric axes in such directions and at such speeds of rotation as to constantly maintain those cutters normal to the path of the web therebetween. By this means said cutters are caused to advance in the direction of the movement of the web and to constantly maintain the most advantageous cutting relation to one another. For coaction with

said cutters, I provide feed rolls for advancing the web at the same speed as that of the forward movement of said cutters during their coaction and which speed of movement is governed by the amount of eccentricity of their eccentric shafts.

Referring now more particularly to Figs. 1 and 2, I provide upper and lower cutter heads 6 and 7 respectively, being opposite duplicates in their general features of mounting and movement. Therefore, a description of the mounting and movement of one thereof will suffice for both.

Referring to cutter head 6, said head is provided with cylindrical portions 8 and 9 at opposite ends thereof, rotatably mounted in rotatable carriers 10 and 11 respectively. Said carriers 10 and 11 turn freely on studs 12 and 13, fixed in side frames 14 and 15 respectively. The common axis of portions 8 and 9 of cutter head 6 is eccentric to the common axis of studs 12 and 13. For rotatable carriers 10 and 11 in unison, I provide those carriers with equal gears 16 and 17 respectively, and which gears are driven from equal gears 18 and 19 similarly fixed to heads 20 and 21 respectively, carrying cutter head 7. Gears 18 and 19 in their turn are driven by gears 22 and 23 respectively, fixed to shaft 24 rotatably mounted in bearings in side frames 14 and 15. On cylindrical portion 9 of cutter head 6 and disposed between said cutter head and carrier 11, is fixed gear 25; also fixed to the inner end of fixed stud 13, is gear 26 equal in size to gear 25. Said gears 25 and 26 are actuated by intermediate gear 27 turning freely on stud 28 fixed to head 11. Thus, when carriers 10 and 11 are rotated in clockwise direction on the common fixed axis of studs 12 and 13, Fig. 2, head 6 will be rotated in anti-clockwise direction on the common eccentric axis of its ends 8 and 9, and, as its gears 25 and 26 are of the same size, said cutter head 6 will be maintained throughout its planetary movement in a constant angular relation to the fixed parts of the machine.

Cutter head 7, being similarly mounted and actuated, will, during its planetary movement, maintain a similar constant angular relation to the fixed parts of the machine and said cutter heads will, therefore, move and be maintained in parallelism with each other.

On either side of cutter heads 6 and 7,

Fig. 2, and normal to the common plane through the fixed axes about which those cutter heads move in circular orbits, I provide tables 29 and 30 over which a web or sheet may be fed between cutter heads 6 and 7. To the right of said cutter heads, Fig. 2, I provide feed rolls 31 and 32 for advancing the web toward the cutters in said heads, and on the left side I provide rolls 33 and 34 for removing the leading end of the web after it has been severed by my improved mechanism. Said two pairs of rolls are provided with the usual gears to cause them to properly coat and said gears are of such a character as to cause rolls 31 and 32 to have the same surface speed as the speed of advancement of the cutters during their coaction, and rolls 33 and 34 are driven at a slightly increased speed so as to take away the severed portion of the blank more rapidly than the speed of travel of the web.

Cutter heads 6 and 7 are provided with coacting cutters respectively. While said cutters may be of any of a variety of characters, I preferably fix to the upper face of cutter head 7 a flat horizontal cutter 35, having a cutting edge 36 parallel with the axis of said cutter head. Adjacent to cutting edge 36 and preferably in the same plane as the upper face of cutter 35, I provide head 7 with a table-like portion 37 for purposes hereinafter described.

Cutter head 6 is provided with cutter 38 for coaction with cutter 35, and said cutter 38 is seated at its upper edge against abutment 39 in said cutter head. Said cutter is, however, free to yield sidewise in one direction against the pressure of springs as 40. Cutter 38 is provided at one end thereof 40 beyond the line of cutting, with a downwardly reaching horn 41 having a beveled face for engagement with one end of cutter 35, whereby, as said cutter 38 is about to pass into engagement with cutter 35, it is 45 guided to accuracy of position therewith by the engagement of said horn 41 with the end of said cutter 35. By this arrangement a slight inaccuracy of coaction between cutter heads 6 and 7, due to backlash of gears or to 50 any other cause, is corrected, and cutters 38 and 35 are always guided into coaction in predetermined relation. Cutter head 6 is preferably provided with a pair of presser feet 42 and 43, the former located to the right, 55 and the latter to the left, of cutter 38, Figs. 2, 4 and 5. These presser feet are urged downwardly against stops in said head by springs as 44, and are efficient for gripping the web against the upper face of cutter 60 35 and table-like portion 37 of head 7, on opposite sides respectively of cutter 38, just prior to the coaction of that cutter with cutter 35, Fig. 4. Said presser feet thus retain the web in control during the cutting operation. After the cutting has been completed,

cutters 35 and 38 separate just prior to the separation of presser feet 42 and 43 from cutter head 7. By this arrangement and sequence of action any tendency of the severed ends of the web to cling to the cutters is prevented.

I claim:

1. Web cutting mechanism including in combination means for advancing a web of material, means for severing the web during its advancement comprising a pair of opposite coacting cutters each of which is pivotally mounted on an axis eccentric to a fixed axis, means for revolving each eccentric axis in one direction about its fixed axis, and means for rotating each cutter in the other direction on its eccentric axis. 75

2. Web cutting mechanism including in combination a pair of opposite coacting cutters each of which is pivotally mounted on an axis eccentric to a fixed axis, and means for rotating said cutters on the eccentric axes at twice the speed of the revolution of said eccentric axes about the fixed axes and in directions opposite to those of their respective eccentric axes about said fixed axes. 85 90

3. Web cutting mechanism including in combination a pair of opposite coacting cutters each of which is pivotally mounted on an axis eccentric to a fixed axis, means for revolving each eccentric axis continuously in one direction about its fixed axis, and means for rotating each cutter continuously in the opposite direction on its eccentric axis. 95

4. Web cutting mechanism including in combination a pair of carriers rotatably mounted in fixed bearings, equal intermeshing gears fixed to said carriers, a cutter rotatably mounted on each carrier on an axis parallel with its carrier axis and eccentric thereto, a gear mounted concentrically with each carrier axis and fixed relatively thereto, an equal gear fixed coaxially on each cutter, and an intermediate gear operably connecting each cutter gear with its respective fixed carrier gear. 100 105

5. Web cutting mechanism including in combination means for advancing a web of material, means for severing the web during its advancement comprising a pair of opposite coacting cutters each of which is pivotally mounted on an axis eccentric to a fixed axis, means for revolving each eccentric about its fixed axis, means for rotating each cutter on its eccentric axis, and means for actuating said advancing means at a speed equal to the speed of revolution of said eccentric axis about said fixed axis. 115 120

6. Web cutting mechanism including in combination means for advancing a web of material, means for severing the web during its advancement comprising a pair of opposite coacting cutters each of which is pivotally mounted at an axis eccentric to a fixed axis, means for revolving each eccentric axis

about its fixed axis and means for rotating each cutter on its eccentric axis, means for actuating said advancing means at a speed equal to the speed of revolution of said eccentric axis about said fixed axis, and means for advancing the severed portion of the web at a speed in excess of the speed of advancement of the web to the cutters.

7. Web cutting mechanism including in combination a pair of opposite cutter heads, each of which is pivotally mounted on an axis eccentric to a fixed axis, means for rotating said cutter heads on their own axes respectively and means for revolving said axes about the fixed axes respectively, means for continuously maintaining said cutter heads in parallelism, a cutter fixed in one of said cutter heads, a cutter in the other cutter head held against movement parallel to the common plane through the fixed axes, said cutter being yieldable transversely to said plane, and means for urging said cutter transversely to engagement with said first-mentioned cutter.
8. Web cutting mechanism including in combination a pair of opposite cutter heads, each of which is pivotally mounted on an axis eccentric to a fixed axis, means for rotating said cutter heads on their own axis respectively and means for revolving said axes about the fixed axes respectively, means for continuously maintaining said cutter heads in parallelism, a cutter in each cutter head, and coacting means on said cutter heads for gripping the web prior to the cutting operation for advancing said web coincidently with said cutters during the cutting operation and for releasing said web after the cutting operation.

ting operation and for releasing said web after the cutting operation.

9. Web cutting mechanism including in combination means for advancing a web of material, a pair of opposite cutter heads each of which is pivotally mounted on an axis eccentric to a fixed axis, means for causing said cutters to coact and during their co-action to advance at the speed of the web advancement, and coacting means on said cutter heads for gripping the web prior to the cutting operation for advancing said web coincidently with said cutters during the cutting operation and for releasing said web after the cutting operation.

10. Web cutting mechanism including in combination means for advancing a web of material, a pair of opposite cutter heads each of which is pivotally mounted on an axis eccentric to a fixed axis, means for causing said cutters to coact and during their co-action to advance at the speed of the web advancement, and coacting means on said cutter heads for gripping the web rearwardly and forwardly of said cutters prior to the cutting operation for advancing said web coincidently with said cutters during the cutting operation and for releasing said web after the cutting operation.

Signed at New York, in the county of New York and State of New York, this 21st day of Oct., 1913, before two subscribing witnesses.

ABRAHAM NOVICK.

MORRIS E. LEVY,
CHAS. W. LA RUE.

It is hereby certified that in Letters Patent No. 1,140,392, granted May 25, 1915, upon the application of Abraham Novick, of New York, N. Y., for an improvement in "Web-Cutting Mechanism," errors appear in the printed specification requiring correction as follows: Page 2, line 129, for the word "at" read *on*; page 3, line 29, for the word "axis" read *axis*; and that the said Letters Patent should be read with these corrections therein that the same may conform to the record of the case in the Patent Office.

Signed and sealed this 15th day of June, A. D., 1915.

[SEAL.]

J. T. NEWTON,

Acting Commissioner of Patents.
